UNITED STATES PATENT OFFICE

1,924,618

COIN SLIDE

Fred L. Mills, Oak Park, Ill., assignor to Mills Novelty Company, Chicago, Ill., a corporation of Illinois

Application April 10, 1930. Serial No. 443,028

7 Claims. (Cl. 194—92)

This invention relates to coin slides and has for an object the provision of a slide or other device for introducing coins into a machine, the operation of which requires the combined use of 5 two or more coins which may be either of the same, or of different, denominations. A slide of this type is particularly useful in connection with vending machines where it is often desirable to adapt the machine to the sale of articles at 10 prices which can not be exactly reached by the use of a single coin. In my co-pending application, Serial No. 421,880, filed January 20, 1930, I have shown a double coin slide of this type as applied to a commodity vending machine for 15 selling staple commodities such as groceries and the like.

An object of the invention is to provide a slide of this character in which the construction is such that other slides of the same general design, but adapted for coins of different denominations, may be readily substituted for the particular slide with which the machine happens to be equipped.

Another object of the invention is to provide 25 a device of this class having a locking mechanism to prevent operation thereof in the event that less than the required number of coins are used, or in case an attempt is made to insert coins of the wrong denomination.

30 Further objects and advantages of the invention will be apparent as I proceed with my specification, which, taken in connection with the accompanying drawing, discloses a preferred embodiment thereof.

35 In the drawing, Fig. 1 is a plan view of a double coin slide constructed in the manner of the invention; and

Fig. 2 is a longitudinal section of the same taken on the line 2—2 of Fig. 1.

40 In the drawing, which illustrates the preferred manner in which I have thus far contemplated applying the principles of the invention, the numeral 5 designates a fixed plate which extends through an opening 6 in a panel mounting 7, the panel ordinarily constituting a wall of the casing which encloses the vending machine or other instrument to which the slide is applied. The plate 5 may be formed of sheet metal and is provided with opposed flanges 8 and 9 which are spaced from the top face of the plate to provide an intermediate opening for receiving the movable mask plate 10. The mask plate 10 is provided with openings 11 and 12 for receiving coins, such for example, as a nickel and a dime, tapered faces being provided in the plate at the outer

edges of each of these openings, as indicated at 13, to permit removal of a coin in case the customer decides not to operate the machine after he has already placed a coin in the slide. The outer end of the mask plate 10 is bent upwardly 60 to afford a finger grip 14 which may be grasped by the operator to operate the slide. The base plate 5 is provided with a pin 15 which extends into a slot 16 in the mask plate 10 to afford a guide for the movement of the mask plate back and forth on the base plate.

In starting the operation of the machine, after placing coins in the openings 11 and 12 in the mask plate 10, the operator shoves the plate inwardly which brings the coins above openings 17 70 and 18 in the inner end of the fixed plate 5. As the coins are carried inwardly their innermost edges drop through the openings 17 and 18 to engage shoulders 19 on bell crank levers 20, said levers being pivoted at 21 to downwardly projecting ears or brackets 22 which are bolted to the under face of the fixed plate 5. The long arms 23 of the bell crank levers 20 engage trip rods 24 which are operatively connected with release mechanism which in turn controls the starting 80 and stopping mechanism of the vending machine. As the coins are moved inwardly against the shoulders 19 of the bell crank levers 20 by further inward movement of the mask plate 10, the bell crank levers 20 are pivoted in a counter-clockwise 85 direction, viewing Fig. 2, which in turn moves the trip rods 24 downwardly to actuate the starting mechanism of the machine. When the coins have been thrust to their innermost positions, they fall through the openings 17 and 18 onto 90 faces 25 of the levers 20. When the trip rods 24 are returned to normal inactive position, under suitable spring action, the bell crank levers 20 are turned back to the position shown in Fig. 2 and the coins slide off from the faces 25 into a suitable 95 coin receptacle.

As the coins are moved inwardly on the mask plate 10 and approach the openings 17 and 18 they are engaged by dogs 26 which are pivotally mounted on a rod 27, journaled at its opposite 100 ends in ears 28, said ears being secured to a top plate 29 which is mounted on an intermediate spacing plate 30, said plates being secured by bolts 31 to fixed plate 5. Spring clips 32, carried by the plate 29, engage over the top edges of the dogs 26 and hold them against the upper face of the coins. Under the tension of the spring 32 the dogs 26 hold the forward edges of the coins in engagement with the shoulders 19 to assure positive turning of the bell crank levers 110.

20. In the embodiment shown, there is provided for each of the openings 17 and 18 an associated release mechanism consisting of bell crank lever 23, trip rod 24, and the spring-pressed dog 26.
5 In case only a single trip rod 24 is needed for releasing the starting mechanism, it is only necessary to provide one of these openings with this release mechanism.

10 The mechanism for locking the slide against operation in case improper coins are used, or in case the operator fails to place coins in both the openings 11 and 12, consists of a pair of dogs 33 which are pivoted at 34 to ears carried on the plate 29. Spring clips 35, secured by bolts 36 to the plate 29, engage the upper edges of the dogs 33. When the mask plate 10 is in the withdrawn position, shown in the drawing, the lower ends of the dogs 33 rest on the inner end of the plate 10. When the proper coins are inserted in the openings 11 and 12, and the mask plate is shoved inwardly, the dogs 33 ride over the top faces of the coins allowing them to pass inwardly to the openings 17 and 18. If a coin is omitted from either of the openings 11 and 12, or if a coin of improper size is used, the corresponding dog 33 will drop through the coin opening and through a slot 37 in the fixed plate 5, assuming the dotted position shown in Fig. 2. In this position the mask plate 10 is locked against further inward movement and the operation of the machine is prevented. When the mask plate is pulled out, the inner concave faces of the dogs 33 engage against the inner edges of the openings 11 and 12, and the dogs ride up into non-obstructing position on top of the mask plate 10.

35 The fixed plate 5, it will be noted, is so positioned in the panel mounting 7 that the locking dogs 33 are housed within the machine and can not be reached by the operator. The plate may be secured to the panel 7 by means of down turned ears 38 which engage against the inner face of the panel. The width of the fixed plate 5 and the moving mask plate 10 may be the same regardless of the size of the coin openings 11 and 12 and the slide, therefore, may be readily substituted for, or replaced by, another slide adapted for different sized coins, without the need of changing the size of the openings 6 in the mounting panel 7.

40 The foregoing detailed description has been given for clearness of understanding only, and no unnecessary limitations should be understood therefrom, but the appended claims should be construed as broadly as permissible in view of the prior art.

50 What I regard as new and desire to secure by Letters Patent is:

1. In a coin-operated machine the combination with a release member having operative connection with the starting mechanism of the machine, of a multiple coin slide for introducing a plurality of coins into the machine to actuate said release member, said slide comprising, a fixed plate mounted in and extending outwardly through an external wall of the machine, said plate being provided near its inner end with openings for passage of coins therethrough, a sliding plate mounted on said fixed plate and provided with individual coin-receiving apertures adapted to be moved into registration with the openings in said fixed plate upon movement of said sliding plate inwardly, locking mechanism operable to prevent movement of said coin-receiving apertures into complete registration with the openings in said fixed plate, said locking mechanism being rendered inoperable by coins of proper denomination.

placed in each of said coin-receiving apertures, and a lever actuated by the coins passing through the aligned apertures in said sliding and fixed plates for actuating said release member to initiate operation of the machine.

80

2. In a coin-operated machine the combination with a release member having operative connection with the starting mechanism of the machine, of a multiple coin slide for introducing a plurality of coins into the machine to actuate said release member, said slide comprising, a fixed plate mounted in and extending outwardly through an external wall of the machine, said plate being provided near its inner end with openings for passage of coins therethrough, a sliding plate mounted on said fixed plate and provided with individual coin-receiving apertures adapted to be moved into registration with the openings in said fixed plate upon movement of said sliding plate inwardly, a coin-operated lever having operative connection with said release member, locking mechanism operable to prevent movement of said coin-receiving apertures into complete registration with the openings in said fixed plate, said locking mechanism being rendered inoperable by 100 coins of proper denominations placed in each of said coin-receiving apertures, and a lever actuated by the coins passing through the aligned apertures in said sliding and fixed plates for actuating said release member to initiate operation of the machine.

85

3. In a coin-operated machine the combination with a release member having operative connection with the starting mechanism of the machine, of a multiple coin slide for transposing a coin from the exterior of the machine into position for actuating said release member, said slide comprising, a fixed plate mounted in and extending outwardly through an external wall of the machine, said plate being provided near its inner end with openings for passage of coins therethrough, a sliding plate mounted on said fixed plate and provided with individual coin-receiving apertures adapted to be moved into registration with the openings in said fixed plate upon movement of 110 said sliding plate inwardly, a lever having one arm operatively connected with said release member, the other arm of said lever being positioned to be engaged by a coin as the inner edge of the latter drops through one of the openings in said fixed plate, and locking mechanism operable to prevent movement of said coin-receiving apertures into complete registration with the openings in said fixed plate, said locking mechanism being rendered inoperable by the placing of coins of proper 115 denomination in each of said coin-receiving apertures.

90

4. In a coin-operated machine, a multiple coin slide comprising a slide rest provided near its inner end with openings for the passage of coins 120 therethrough, a manually operable slide mounted on said rest and provided with coin-receiving pockets positioned to register with said openings in the rest when the slide is moved inwardly, and means operative upon the passage of a coin 125 through one of the openings in the rest to start the operation of the machine, said means comprising a lever having one arm operatively connected with the starting mechanism of the machine, the other arm of said lever being positioned to be engaged and actuated by a coin passing through an opening in the slide.

95

5. In a coin-operated machine the combination with a vertically movable release member having operative connection with the starting 130 mechanism of the machine, of a multiple coin slide for introducing a plurality of coins into the machine to actuate said release member, said slide comprising, a fixed plate mounted in and extending outwardly through an external wall of the machine, said plate being provided near its inner end with openings for passage of coins therethrough, a sliding plate mounted on said fixed plate and provided with individual coin-receiving apertures adapted to be moved into registration with the openings in said fixed plate upon movement of said sliding plate inwardly, locking mechanism operable to prevent movement of said coin-receiving apertures into complete registration with the openings in said fixed plate, said locking mechanism being rendered inoperable by 135 coins of proper denomination placed in each of said coin-receiving apertures.

100

6. In a coin-operated machine the combination with a release member having operative connection with the starting mechanism of the machine, of a multiple coin slide for introducing a plurality of coins into the machine to actuate said release member, said slide comprising, a fixed plate mounted in and extending outwardly through an external wall of the machine, said plate being provided near its inner end with openings for passage of coins therethrough, a sliding plate mounted on said fixed plate and provided with individual coin-receiving apertures adapted to be moved into registration with the openings in said fixed plate upon movement of said sliding plate inwardly, locking mechanism operable to prevent movement of said coin-receiving apertures into complete registration with the openings in said fixed plate, said locking mechanism being rendered inoperable by 140 coins of proper denomination placed in each of said coin-receiving apertures.

105

7. In a coin-operated machine the combination with a release member having operative connection with the starting mechanism of the machine, of a multiple coin slide for introducing a plurality of coins into the machine to actuate said release member, said slide comprising, a fixed plate mounted in and extending outwardly through an external wall of the machine, said plate being provided near its inner end with openings for passage of coins therethrough, a sliding plate mounted on said fixed plate and provided with individual coin-receiving apertures adapted to be moved into registration with the openings in said fixed plate upon movement of said sliding plate inwardly, locking mechanism operable to prevent movement of said coin-receiving apertures into complete registration with the openings in said fixed plate, said locking mechanism being rendered inoperable by 145 coins of proper denomination placed in each of said coin-receiving apertures.

150

- mechanism of the machine of a double coin slide for transposing a coin from the exterior of the machine into position for actuating said release member, said slide comprising a fixed plate extending through an external wall of the machine and provided near its inner end with a pair of openings for passage of coins therethrough, a manually operable slide mounted on said fixed plate and provided with coin-receiving apertures adapted to be moved into registration with the openings in said fixed plate upon movement of the slide inwardly, spring-actuated detents disposed in the line of movement of said coin-receiving apertures and operable to prevent movement 5 of the latter into complete registration with the openings in said fixed plate, said detents being rendered inoperative by the presence of a coin of proper denomination in each of said apertures in the slide, a coin-operated lever having one arm operatively connected with said release member, the other arm of said lever being positioned to be engaged by a coin as the inner edge of the latter drops through one of the openings in said fixed plate, and spring-pressed means for holding the 10 edge of the coin in engagement with said last-mentioned arm of the lever.
6. In a coin-operated machine, a multiple coin slide comprising a slide rest provided near its inner end with openings for the passage of coins therethrough, a manually operable slide mounted 15 on said rest and provided with coin-receiving pockets positioned to register with said openings in the rest when the slide is moved inwardly, means operative upon the passage of a coin through one of the openings in the rest to start the operation of the machine, said means comprising a member operatively connected with the starting mechanism of the machine and positioned to be engaged and actuated by a coin passing through an opening in the slide, and means for arresting the movement of said slide short of the coin-releasing position thereof in the absence of proper coins in each of the pockets of said slide. 20
7. In a coin-operated machine, a coin slide comprising a slide rest provided near its inner end with an opening for the passage of a coin therethrough, a manually operable slide mounted on said rest and provided with a coin-receiving pocket positioned to register with said opening in the rest when the slide is moved inwardly, means operative upon the passage of a coin through said opening in the rest to start the operation of the machine, said means comprising a member operatively connected with the starting mechanism of the machine and positioned to be engaged and actuated by a coin passing through said opening in the slide, and means for pressing the coin through the aligned openings in said slide and slide rest to actuate said member. 25
